UNITED STATES PATENT OFFICE.

FRED LACEY, OF VALLEYFIELD, CANADA.

SPOOL-LIFTER FOR YARN-SPOOLING MACHINES.

SPECIFICATION forming part of Letters Patent No. 640,474, dated January 2, 1900.

Application filed April 27, 1898. Serial No. 679,013. (No model.)

To all whom it may concern:

Be it known that I, FRED LACEY, a citizen of the United States, residing at Valleyfield, in the county of Beauharnois and Province 5 of Quebec, Dominion of Canada, have invented certain new and useful Improvements in Spool-Lifters for Yarn-Spooling Machines, of which the following is a specification, reference being had therein to the accompanying 10 drawings.

Among the operations to which yarns are subjected in the process of manufacture is that of spooling, in which the yarns from a number of cops or bobbins successively are 15 wound onto a large spool, the last end of the yarn from a cop or bobbin as the latter becomes exhausted being united to the beginning of the yarn on a fresh cop or bobbin, and so on in succession until the spool is full. 20 From time to time also in the course of the spooling it becomes necessary to arrest the winding operation and to break the yarn which is being wound from a cop or bobbin onto the spool for the purpose of removing 25 from such yarn a knot or the like, the broken ends afterward being united by the spooler-tender by means of a carefully-tied knot and the winding being allowed to proceed. The spools onto which the winding is effected are 30 mounted upon rotating spindles, and whenever it is desired to effect the uniting of two ends of yarn—that is to say, whenever one cop or bobbin becomes exhausted and a fresh one is substituted—or a knot has to be removed 35 it is necessary for the spooler-tender to restrain the spool from rotation until after the knot has been tied. Ordinarily it becomes necessary for the spooler-tender to hold the spool from rotating with its spindle by his 40 hand, and this necessity renders it more or less inconvenient for him to effect the tying of the knot. It is preferred in some cases that the tying shall be effected by the formation of a weaver's knot, which in some respects is 45 the best for the purpose and occasions the least trouble in weaving; but this knot requires the use of both hands and is a difficult one to tie when the duty of holding the spool from rotation by hand devolves also upon the 50 spooler-tender.

The object of the invention is to provide a simple and convenient device by means of

which the spool may be lifted out of driving engagement with its spindle whenever it is desired to arrest the rotation of the spool for 55 the purpose of tying a knot or for any other purpose, the said device operating to hold the spool lifted while the spooler-tender performs the necessary operations, both the hands of the spooler-tender being left free for such operations.

The invention will be described first fully with reference to the accompanying drawings, in which I have illustrated the best embodiments thereof which I have yet contrived, 65 after which the essential and distinguishing characteristics of the invention will be more particularly pointed out and distinctly defined in the claims at the close of this specification.

Figure 1 of the accompanying drawings is a view showing in front elevation portions of a spooling-machine with one embodiment of my invention applied thereto, only such parts being illustrated as are required in order to 75 enable the invention to be understood. Fig. 2 is a view in vertical section on the dotted line 2 2 of Fig. 1 looking in the direction of the arrows at the ends of such line. Fig. 3 is a view showing in front elevation, detached, one of 80 the spool-lifting devices of Fig. 1. Fig. 4 is an edge view thereof looking from the right-hand side in Fig. 3. Fig. 5 is a view like unto Fig. 1, but showing a second embodiment of the invention. Fig. 6 is a view in vertical section 85 on the dotted line 6 6 of Fig. 5 looking in the direction of the arrows at the ends of such line. Fig. 7 is a view showing in front elevation, detached, a spool-lifting device of the kind shown in Fig. 5. Fig. 8 is an edge view 90 thereof looking from the right-hand side in Fig. 7. Fig. 9 is a view in horizontal section on the dotted line 9 9 of Fig. 7. Fig. 10 is a view corresponding with Fig. 3, showing a modification. Fig. 11 is a plan of the fork of 95 Fig. 10. Fig. 12 is a side elevation of the parts which appear in Fig. 10. Fig. 13 is a view in elevation showing another modification.

Reference will be had first to the showing 100 in Figs. 1 to 4. 1 designates the framing of the spooling-machine, and 2 the spindle-rail. 3 3 designate the spindles, the same being rotatably mounted in the said spindle-rail. 4 des-

ignates the spindle-driving drum, and 5 5 designate the bands passing around the said drum and also around the spindle-whirls. 6 5 designates the supporting-rod for the bobbin or cop holders 7 7, and 8 8 designate yarn guides or clearers, which are mounted upon the supporting-rod 9, the usual spool-box being designated 10. The frictional driving-disks upon the spindle are designated 11 11, 10 and 12 12 designate the spools which are mounted on the spindles. The yarns 13 13 which are being wound are shown as proceeding from the bobbins 14 14 contained in the holders 7 7 and passing over the rod 9 and 15 through the yarn guides or clearers 8 8 to the said spools 12 12. 15 15 designate small frames or castings, the same being fastened by means of bolts or screws to the front of the spool-box 10, one of such frames or castings 20 usually being located adjacent to each spindle. 16 designates a small hand-operated lever which is connected pivotally to each frame or casting 15 and standing in a vertical position. The said lever is connected with the 25 said frame or casting by a pivotal pin or rivet 17, which is applied to the said frame or casting near the lower end of the latter, the said pin or rivet being headed so as to retain the lever thereon. The lower end of the lever 16 30 is provided with a projection 18, which may be constituted by a roller that is journaled on the said lower end of the lever, the said roller or other projection extending under the lower head of the spool 12, which is carried by the 35 spindle 11 in front of the stand 15. The main portion of the lever extends upward from the pivotal pin 17, and near the upper end of the frame or casting 15 said portion of the lever passes through a slot or opening 19 40 in the frame or casting, the said upper end of the latter being bent forward, so that the bar 20 above the said slot or opening 19 lies in front of the plane occupied by the lever 16. The bar 20 serves as a keeper for the upper 45 portion of lever 16, and the extent of the lateral swing of said lever is limited by the ends 21 21 of the slot or opening 19. In the upper side of the bar 20 is a notch or depression 22 to receive the pin 23, projecting from the lever 50 16 over the bar 20, the remainder of the upper surface of the said bar being concentric, or substantially so, with the pivotal pin or rivet 17. The lever is slotted longitudinally at 24, where the pivotal pin 17 passes therethrough, 55 so that the weight of the lever 16 will cause the pin 23 to rest and slide on the upper surface of the bar 20 until in the movement of the lever the notch or depression 22 is reached, when the lever will drop, the pin entering into 60 the said notch or depression, and thereby the lever will be locked in the position which it then occupies until the pin is raised or pressed out of the notch or depression. The upper end of lever 16 projects above the top of frame 65 or casting 15 and is conveniently shaped, as by flattening and widening the same, as represented in Figs. 3 and 4, to fit the same for

being taken hold of or pressed against by the fingers of one of the spooler-tender's hands. The lever is unbalanced in consequence of 70 the fact that the part thereof to which roller 18 is applied projects to one side of the center of gravity of the lever, so that whenever the pin 23 is disengaged from the notch or depression in the bar 20 of the frame or casting 15 75 the lever gravitates into the position in which it is represented at the left in Fig. 1 and in Fig. 3, such being the normal position of the lever, and being occupied by the latter while the winding is proceeding in proper manner 80 on the spool carried by the spindle with which the lever is associated in the machine. When it is desired to stop the rotation of such spool, the hand-lever 16 is pushed over until the pin 23 drops into the notch or depression 22, 85 thereby raising the spool out of driving engagement with the spindle, the hand-lever being held locked in position to keep the spool raised until the pin 23 has been disengaged from the notch or depression 22 and 90 the lever has been allowed to swing back into its normal position. The position of hand-lever 16 relatively to the spindle carrying the spool with which it coacts is such as to render it convenient for the spooler-tender 95 after having moved the said hand-lever by one hand and thereby stopped the spool to employ the same hand for the purpose of raising the spool and turning the latter to find the end of the yarn that is wound thereon. 100

In Figs. 1 to 3 the main portion of the hand-lever 16 is straight and extends upward in line with the pivot of the lever. In this case the distance of the roller 18 laterally from the said pivot compels the stand to be mounted 105 in a position intermediate the spindle with which it is associated in use and the next spindle. This is not so convenient for the spooler-tender as it would be to have the casting and main portion of the lever located immediately in line with the corresponding spindle and at the rear of such spindle. This latter arrangement may be secured, if desired, by giving a bent or angular form to the hand-lever, so as to dispose the handle of the lever and the roller 18 in line with each other. 110 An arrangement embodying this last-mentioned feature is shown in Figs. 5 to 8. Figs. 5 to 9, in addition, illustrate another device which may be utilized for the purpose of detaining or holding the hand-lever, which therein is designated 161, in the position which maintains the spool out of driving contact with its spindle. In these figures 25 designates a flat spring that extends across in front 115 of the upper part of the hand-lever 16 and serves in part as a guide for the said hand-lever 16. One end of the said spring 25 is fastened, as by means of a rivet 26 or other securing device, to a raised portion 27 on one 120 side of the frame or casing 26. The other end of said spring plays in a notch 28, formed in a corresponding raised portion 29 on the other side of the frame or casing. At an in-

termidiate point in its length the spring is bent so as to form a projection, as 30, extending into the path of movement of the hand-lever. This projecting portion 30 of the 5 spring serves to hold the hand-lever from returning after the same has been moved over to the right-hand side into the position in which it serves to raise the spool out of driving engagement with its spindle. 10 As will be apparent from the foregoing the operative portion of the spool-lifter consists of a single hand-operated lever gravitating normally into an inoperative position, the said lever occupying a vertical or upright (or substantially such) position near the spindle with 15 which it is associated in use and having its upper portion extended into position adjacent to the upper ends of the spindle and spool to enable such portion to be acted upon by the fingers of the hand of the spooler-tender while such hand is bearing upon the top of the spool or just above the same and the lower portion of the hand-lever having a projection which is offset laterally with respect to the 20 pivot of the hand-lever to engage with the spool and raise it in the movement of the hand-lever. With the said hand-lever is combined a means of detaining or holding the same in its abnormal position to keep the 25 spool raised out of driving engagement with the spindle.

As will be obvious, instead of relying upon gravity for the purpose of causing the hand-lever 16 to assume and retain its normal inoperative position I may utilize a spring connected with the said hand-lever.

Figs. 10, 11, and 12 illustrate a modification in which the projection on the lower end of the hand-lever (therein designated 162) is in 40 the form of a fork, (designated 31,) the said fork being held to the hand-lever by means of a rivet or the like, as 32, and having, if desired, capacity to swivel on the said rivet. The arms of the lifter-fork project forwardly 45 on opposite sides of the spindle and beneath the position of the lower spool-head. This fork may be applied to any of the forms of the hand-lever, including the double form of such lever, which is shown in Fig. 13. The 50 latter form has been devised with the idea in view of enabling one hand-lever (here designated 163) to serve for use in connection with two adjacent spindles. It has oppositely-projecting arms, each carrying a roller 18 or a fork 31. One arm and its roller or fork are intended to coact with the spool on one spindle and the other arm and its roller or fork are intended to coact with the spool on an adjacent 55 spindle. This form of hand-lever will occupy normally an intermediate position, with both its rollers, forks, or other spool-raising projections depressed out of engagement with the spools. It may be swung in either direction from its normal intermediate position, according as it is desired to elevate the spool at

the right or that at the left, and is provided with a detent device to hold it in either of its operative or abnormal positions. In Fig. 13 I have shown the hand-lever slotted at 24, as in Figs. 1 to 3, the bracket or stand 15 being substantially the same as in Figs. 1 to 3, but having a notch 22 at each side of the intermediate position of the upwardly-extending arm of the hand-lever.

I claim as my invention—

1. The combination with the spindle of a yarn-spooling machine of the hand-lever standing adjacent to the spindle at the rear of the latter with its arm extending upward into proximity to the top of the spindle and in position to be acted upon by the operative's hand which also takes hold of the upper head of the spool on such spindle, the said hand-lever having on its lower portion a projection laterally offset with respect to the pivot of the lever to move upwardly and directly lift the spool on the spindle when the hand-lever is moved by pressure exerted on its upper portion by such hand, substantially as described.

2. The combination with the spindle of a yarn-spooling machine, of the hand-lever standing adjacent to the spindle at the rear of the latter with its arm extending upward into proximity to the top of the spindle and in position to be acted upon by the operative's hand which also takes hold of the spool on such spindle, the said hand-lever having on its lower portion a projection laterally offset with respect to the pivot of the lever to move upwardly and directly lift the spool on the spindle when the hand-lever is turned by pressure exerted on its upper portion by such hand, and also having a detent device to retain it in the position thereof which holds the spool raised, substantially as described.

3. The combination with the spindle of a yarn-spooling machine, of a hand-lever occupying normally an inoperative position, movable vertically at its pivot, having its upper portion extended into position adjacent to the top of the spindle to enable it to be acted upon by the hand of the spooler-tender which takes hold of the spool on such spindle, and having on its lower portion a projection which engages and lifts the spool on the spindle, the said upper portion of the lever having also a projection, and a fixed bar on the upper surface of which the latter projection rests and moves, the said bar having a notch or depression which the said projection enters to hold or detain the lever in the position thereof which keeps the spool raised, substantially as described.

In testimony whereof I affix my signature in presence of two witnesses.

FRED LACEY.
